UNITED STATES PATENT OFFICE

HERBERT N. RIDGWAY, OF WINTHROP, MASSACHUSETTS

KEY TAG

Application filed August 14, 1928. Serial No. 299,469.

This invention relates to key tags such as are used for identifying keys, and the object of the invention is to provide a novel key tag which can be readily applied to any key without the use of any tools and by means of which the key can be easily identified.

My improved key tag has a general hood shape and is adapted to fit over and enclose the head of the key, said tag having an aperture, therethrough which is situated to be aligned with the ring-receiving aperture in the key so that when the tagged key is put on the ring the latter will pass through both the aperture in the key and the aperture in the tag and will thus hold the tag in position. Furthermore, the fact that the tag has a hood shape and embraces the head of the key serves as additional means for retaining the tag in proper position relative to the key when the latter is on the ring.

In order to give an understanding of my invention I have illustrated in the drawings some selected embodiments thereof which will now be described, after which the novel features will be pointed out in the appended claims.

In the drawings,

Figure 1 is a perspective view of a key tag embodying my invention;

Fig. 2 shows the tag applied to a key and the latter fastened on a key ring;

Fig. 3 is a view similar to Fig. 2, but illustrating the tag as used in connection with a different form of key;

Fig. 4 is a section on the line 4—4, Fig. 2;

Fig. 5 is a view similar to Fig. 4, but showing a different embodiment of the invention;

Fig. 6 is a perspective view illustrating a key tag having a different construction from that shown in Figs. 1 to 5;

Fig. 7 is a view of the label member;

Fig. 8 is a perspective view of a still different embodiment of the invention.

Fig. 9 is a section on line 9—9, Fig. 8.

As stated above, my improved key tag is a hood-shaped device which is adapted to fit over and enclose the head of the key. Such a tag is shown at 1 in Fig. 1, and it is formed with the two separated sides 2 and

3 which are connected at their peripheries by the wall 4. The side walls 2, 3 will preferably have a generally semi-circular shape, although the precise shape is not important. The hood-shaped device is open at its lower end as shown at 5 to permit the head 6 of a key 7 to be inserted and the device will preferably be of sufficient size to substantially enclose the head 6 of the key.

The side walls 2 and 3 are provided with apertures 11 which are so located as to be in line with the ring-receiving aperture 8 of the key 7 when the head of the key is inserted into the hood.

The hood-shaped device 1 has associated with it a word or legend by which the key to which it is applied may be identified. This identifying word or legend may be placed directly on one of the side walls 2 or 3, or it may be on a separate piece of paper, metal or fibre, which is enclosed within the hood and which may be read either by providing the hood with a window or sight opening, or by making the hood of some transparent material such as celluloid.

In the construction shown in Figs. 1, 2 and 3 the identifying word or legend is imprinted or placed directly on one of the side faces of the hood. The tag shown in Figs. 1, 2 and 3 may be made of any suitable material adapted to have the identifying word written or printed thereon.

Another form of the invention is shown in Fig. 5, in which the hood is provided with a protective covering, preferably of transparent material such as celluloid. In this embodiment the complete tag comprises the inner member which has the identifying word or legend printed or written or otherwise impressed thereon and the outer protective covering 9 which is transparent and which, as stated above, may be made of celluloid or any other material through which the word or legend on the inner member may be read. An advantage of the construction shown in Fig. 5 is that the protective covering 9 prevents the identifying word from becoming worn or rubbed off as the key is carried in the pocket.

Another form of the invention is shown in

Fig. 6. In this embodiment the hood member 1 is preferably formed of some non-transparent material, and it is provided with a window or sight opening 12 through which the identifying word or legend may be seen. Such word or legend is placed on a piece of paper 13 or other sheet material which is situated within the hood member and is located between the side having the sight opening and the key. The sheet or label member 13 will preferably have an aperture 14 therein which is aligned with the apertures 11 in the hood member so that when the tag is applied to the key and the latter is placed on a key ring 10 the key ring will hold the label 13 in position.

Another embodiment of the invention is shown in Fig. 8. In this construction the hood member, or at least one side thereof, is made of transparent material such, for instance, as celluloid and the identifying word or legend is placed on a label member 13 which is situated within the transparent hood and which is visible therethrough. This label member 13 will preferably have the construction shown in Fig. 7, that is, it is a piece of sheet material of the proper shape bearing the identifying legend and having an aperture 14 situated to be aligned with the apertures 11 in the hood member.

A key tag embodying my invention can be easily applied to any key regardless of the shape of the key. It is not essential that the tag should be of the same shape as the head of the key, since a semi-circular shape such as shown in the drawings can be used with keys having heads of various shapes.

This is clearly shown in Figs. 2 and 3, Fig. 2 showing the hood applied to a key having a round head, and Fig. 3 showing it applied to a key having a diamond-shaped head.

The hood device may be made with relatively thin walls so that when applied to the key it adds very little to the transverse thickness.

The tag can be easily slipped onto the head of any key, and when the key is placed on the key ring 10 with the latter passing through the apertures 11 of the tag and the apertures 8 of the key the tag will be securely retained in position. The key ring prevents the tag from slipping off from the end of the key and the side walls 4 prevent the tag from swinging with relation to the key, and hence said tag will be retained in proper position so long as the key is on a key ring 10.

The device has the advantage that it can be applied to any key without making any change in the key or without the necessity of using any tool for this purpose, and when applied to the key it provides a sure identification for the key.

While I have illustrated herein several embodiments of the invention, yet I do not wish to be limited to the constructions shown,

as various other constructions would come within the scope of the appended claim.

I claim:

The combination with a key having a head and a shank, of a hood-shaped key tag member open at one edge for the insertion thereinto of the head of the key, said hood-shaped member having an opening which is in alignment with the key ring receiving opening of the key when the head of the key is in the hood member, and a key ring passing through the aligned apertures of the hood member and key head and retaining the hood member on the head, the dimension of the hood member in the direction of the length of the key being such that the entire shank of the key projects beyond the hood member.

In testimony whereof, I have signed my name to this specification.
